UNITED STATES PATENT OFFICE.

IMLAH A. MANLEY, OF CANON, GEORGIA, ASSIGNOR TO WORLEY ADAMS, OF ROYSTON, GEORGIA.

PLOW.

1,190,438.

Specification of Letters Patent.

Patented July 11, 1916.

Application filed August 27, 1912. Serial No. 717,337.

To all whom it may concern:

Be it known that I, IMLAH A. MANLEY, a citizen of the United States, residing at Canon, in the county of Franklin and State 5 of Georgia, have invented new and useful Improvements in Plows, of which the following is a specification.

This invention relates to plows, and it has for its object to provide simple and efficient means whereby the plow foot may be adjusted so as to present the blade at various angles with respect to the surface of the ground.

A further object of the invention is to 15 produce a lever of simple and improved construction, whereby the plow foot may be actuated and retained at various adjustments, said lever having arms on which segment racks by adjusting the plow foot 20 may be secured, and said arms being extended beyond the rack segments to guide the plow foot.

With these and other ends in view which 25 will readily appear as the nature of the invention is better understood, the same consists in the improved construction and novel arrangement and combination of parts which will be hereinafter fully described and particularly pointed out in the claim.

30 In the accompanying drawing has been illustrated a simple and preferred form of the invention, it being, however, understood that no limitation is necessarily made to the precise structural details therein exhibited, 35 but that changes, alterations and modifications within the scope of the claim may be resorted to when desired.

In the drawing,—Figure 1 is a side elevation of a plow constructed in accordance 40 with the invention. Fig. 2 is a sectional elevation taken on the line 2—2 in Fig. 1. Fig. 3 is a perspective view showing the adjusting lever detached.

45 Corresponding parts in the several figures are denoted by like characters of reference.

The plow beam 1 is provided with the usual handles 2 whereby it may be guided. The plow foot F is composed of two bars 50 or side members 3, 3 which are positioned adjacent to opposite sides of the beam with which they are pivotally connected by means of a bolt or pivot member 4. The lower end of the foot supports the ground engaging 55 blade 5. The upper forward ends of the

side bars 3 are formed with arcuate racks 6 which are concentric with the axis of the pivot member 4.

The lever L whereby the plow foot is adjusted and retained at various angles is composed of two bars or side members 7, the lower ends of which are spaced apart, as shown, said side members being provided intermediate their upper and lower ends with shoulders or offsets 8 whereby the upper ends of the side members are positioned closer together, as shown, to form a handle 9. The lower extremities of the side members 7 are provided with lugs or arms 10 which extend rearwardly with respect 70 to the pivot member 11 whereby the lever is fulcrumed on the plow beam. Firmly secured upon the inner faces of the side members 7 and arms 10 of the lever L are segmental rack plates 12 that mesh with the 75 rack segments 6 of the plow foot, thus enabling the latter to be adjusted about the axis of the pivot 4 by means of the lever 11. Said lever is provided with a spring actuated latch 13 of well known construction, 80 said latch engaging a rack segment 14 which is mounted on the plow beam, thus enabling the plow foot to be secured in any position to which it may be adjusted.

The rack plates 12 which are secured on 85 the limbs or side members of the lever L will be held very firmly, being secured not only to the limbs, but also to the rearwardly extending lugs or arms 10. Should said rack plates break, they may be easily replaced at a trifling expense.

It will be noted that the lugs or arms 10 are made of sufficient length to overlap the rack segments 6 of the plow foot, thereby securely holding said segments against lateral displacement which would interfere with the operation of the plow, and thus providing an extremely simple and durable, as well as inexpensive, construction.

Having thus described the invention, what 100 is claimed as new, is:—

In a device of the class described, the combination with a plow beam and a plow standard pivoted thereon, said standard having side members positioned adjacent to opposite sides of the beam, and said side members being provided with segment racks at their front ends, of a bifurcated lever straddling the beam and extending upwardly therefrom, said lever having limbs provided 105 110

with rearwardly extending arms, a pivot member extending through the beam and through the lever at an angle between the limbs and the rearwardly extending arms, said arms being extended rearwardly to overlap the rack segments at the forward ends of the limbs of the standard, rack segments mounted on the pivot member in engagement with the first mentioned rack segments, fastening means whereby the last mentioned rack segments are secured upon the limbs and arms of the lever, and means for retaining the lever and related parts at various ad-

justments, said means consisting of a notched segment bar secured on the plow beam between the limbs of the lever which is thereby guided, and a spring actuated stop member carried by the lever and engaging the notched bar. 15

In testimony whereof I affix my signature 20 in presence of two witnesses.

IMLAH A. MANLEY.
